DESIGN FOR A HOODED STORM COAT FOR DOGS

Rose Ann Cheney, Savannah, Ga.

Application April 17, 1946, Serial No. 128,662

Term of patent 14 years

(Cl. D38—10)

To all whom it may concern:

Be it known that I, Rose Ann Cheney, a citizen of the United States, residing at Savannah, in the county of Chatham and State of Georgia, have invented, a new, original, and ornamental Design for a Hooded Storm Coat for Dogs, of which the following is a specification, reference being had to the accompanying drawing, forming part thereof.

In the drawing:

Fig. 1 is a top plan view of a hooded storm coat for dogs showing my new design;

Fig. 2 is a side view thereof;

Fig. 3 is a bottom plan view; and

Fig. 4 is a transverse sectional view on the line 4—4 of Fig. 3.

My design for a hooded storm coat for dogs is characterized by the two elongated openings for the front legs of a dog in combination with the neck portion and the hood, all of the specific configuration as illustrated.

I claim:

The ornamental design for a hooded storm coat for dogs, substantially as shown and described.

ROSE ANN CHENEY.
